UNITED STATES PATENT OFFICE.

GEORGE W. COPE AND WILLIAM L. BERTRAM, OF DETROIT, MICHIGAN.

DESIGN FOR A STOVE.

40,810.

Specification for Design.

Patented Aug. 2, 1910.

Application filed June 2, 1910. Serial No. 584,712. Term of patent 7 years.

To all whom it may concern:

Be it known that we, GEORGE W. COPE and WILLIAM L. BERTRAM, both citizens of the United States, residing at Detroit, county of Wayne, State of Michigan, have invented a new, original, and ornamental Design for Stoves, of which the following is a specification, reference being had therein to the accompanying drawing, forming part thereof.

The figure is a perspective of a stove, showing our new design.

We claim:

The ornamental design for a stove as shown.

GEORGE W. COPE.
WILLIAM L. BERTRAM.
